(57) **CLAIM**

The ornamental design for a spray paint applicator, as shown and described.

DESCRIPTION

FIG. 1 is a perspective view of a spray paint applicator showing the new design;

FIG. 2 is a left side view thereof;

FIG. 3 is a right side view thereof;

FIG. 4 is an enlarged front view thereof;

FIG. 5 is an enlarged back view thereof;

FIG. 6 is a top view thereof; and,

FIG. 7 is a bottom view thereof.

The broken lines in the drawings depict parts of the spray paint applicator that form no part of the claimed design.

1 Claim, 7 Drawing Sheets
